UNITED STATES PATENT OFFICE.

CHARLES MICHEL, JR., CHARLES KOLLEN, AND GUSTAVE HERTZOG, OF REIMS, FRANCE.

APPARATUS FOR TANNING.

SPECIFICATION forming part of Letters Patent No. 242,954, dated June 14, 1881.

Application filed May 7, 1881. (No model.)

To all whom it may concern:

Be it known that we, CHARLES MICHEL, Jr., CHARLES KOLLEN, and GUSTAVE HERTZOG, all citizens of France, and all residing at 5 Reims, in the Republic of France, have invented a new and useful Improved Apparatus for Tanning, of which the following is a specification.

All the improvements in the methods and 10 apparatus heretofore employed in tanning have not enabled the problem of rapid tanning to be solved, it being still necessary to subject the hides for months to this process. Some 15 special apparatus for accelerating the process have from time to time been patented, but they have not been practically successful, either because the processes were too expensive or because the tanned hides had not the desired qualities.

20 The apparatus to which the present invention relates obviates these difficulties by permitting calf-skins to be tanned in a few hours, and cow or ox hides in about forty-eight hours, while at the same time affording the leather 25 produced all the flexibility and firmness indispensable to a perfect product.

The essential objects of these apparatus are, first, to regulate at will during the operation 30 of tanning the temperature of the liquors in the operating-tank and in the receptacle containing the hides to be tanned; second, to regulate the density of the liquors in the said receptacle, and also to change their nature, as required, for consecutive processes without interrupting the operation of the apparatus; 35 third, the clarifying of the liquors used in former processes in order to enable them to serve for future processes; and it is by the combination of these means that according to the present invention rapid tanning may be effected.

The accompanying drawings show the combined apparatus which we employ, Figure 1 showing a longitudinal section, and Fig. 2 a plan.

40 It consists of a receptacle or drum, A, a suction and force pump, B, (shown in elevation in Fig. 1,) an operating-tank, E, two filters, I I, of which one is shown in elevation in Fig. 1, and of reserve-tanks K L J.

The drum A, constructed of wood, revolves 50 upon a horizontal axis, its trunnions, which are secured to its sides, as shown, being carried in bearings on standards fixed to the foundation. On the one trunnion is fixed a worm-wheel, A', in gear with a worm, A², 55 driven by fast and loose pulleys, so as to cause the drum to perform about ten to fifteen revolutions in a minute, according to the nature of the hides. The other trunnion is hollow to allow the passage through it of two pipes, a 60 and b, carried by a bracket. The one pipe, a, is bent downward inside the drum, so as to descend to the lowest point thereof and enable the liquor to be withdrawn therefrom through it by means of a pump, B, of any suitable construction. The second pipe, b, communicates with a reservoir, E, which will be presently described. The drum has a double side or partition, A³, having perforations, so as to protect the pipes a b while the drum revolves, and a 70 charging-hole, D, closed hermetically by a cover, so as to prevent any escape of liquor while rotating. The interior of the drum is furnished with projections of wood of different lengths, so as to cause the skins to be effectively moved about and beaten during the operation. 75

The operating-tank E is mounted upon a raised platform, E', by which access is gained all round it. It is closed with the exception 80 of an opening at top, in which is suspended a basket, E², of wicker-work or perforated metal, through which the liquor may be introduced.

The pump B can force the liquors of the drum A into the tank E by means of the pipes d d, 85 the liquor being made to pass through a refrigerator, F, consisting of a tubular receptacle, through which cold water is made to flow, for which purpose the casing of the receptacle is connected by a branch pipe, f, with stop-cock h, to a pipe, g, leading to a water-supply under pressure, while the discharge is conveyed by the pipes i and j to a discharge-channel, G. The liquor passing through d enters a number of small tubes in the refrigerator, so 90 as to offer large cooling-surfaces to the liquor in a well-known manner, and issues at the upper end into the upper pipe, d, again, leading 95

into the tank E. On the bottom of this tank is a worm, *k*, through which steam may be passed so as to raise the liquor to a certain temperature, which is indicated by a thermometer at H, and by means of a pipe, *b*, provided with a stop-cock, the liquor may be allowed to pass down from the tank E into the drum A again. The operating-tank E may also be emptied by means of a pipe, *l*, having cocks *m m*, by opening which the liquor is discharged into filters I I, placed over tanks J, which receive the filtered liquors, and from which these can be again conveyed into the tank E by means of the pipe *n* and force-pump B. The filters consist of a wooden receptacle having at top a tray of perforated copper, and below this, on a perforated tray, at O, small pebbles or gravel, below which, at P, is another tray carrying a layer of charcoal and Spanish white or other suitable substances, which purify and clarify the liquor so as to renovate its tanning properties. The several trays can be readily removed for cleansing purposes. If, notwithstanding this triple filtration, it should be necessary to leave the filtered liquors quiescent, in order to clarify still more by subsidence, cocks may be provided in the filtering-tanks at different heights for drawing off the supernatant clear liquor, as indicated at 1 2 3 4. The reserve-tanks K L J communicate on the one hand with the operating-tank E by pipes *g*, and on the other hand, by pipes *a*, with the suction-pipe *n* of the pump B. The operation of tanning is carried out as follows: A certain quantity—such as from one thousand to fourteen hundred pounds weight—of hides are introduced into the drum A through the opening at D, which is then closed, and the drum is rotated after having been charged through the pipe *b* from tank E with a certain quantity of liquor composed of tanning extracts and other essences ordinarily employed in tanning, the supply being regulated by a cock. The liquor in the operating-tank requiring to be maintained at a certain temperature, this is effected either by heating by means of the steam-coil *k* or by means of fermentation in the drum, or, on the other hand, by cooling by the action of the refrigerator F, which can be regulated by the cocks on the cold-water supply. All attempts hitherto made to effect the tanning operation in a revolving drum have failed for the want of means for properly regulating the temperature of the interior of the drum. Leather produced by tanning at too high a temperature has no consistency, and is rigid and liable to crack, and, even though it should possess the requisite density, the shrinking which may always result in its use renders it practically useless. If, on the other hand, the temperature is not raised sufficiently high at the proper time, the penetration of the liquor is not facilitated by the swelling of the hides, and it cannot be effected afterward if the fermentation is not produced at the proper moment.

In order to observe accurately the temperature of the drum, a thermometer is provided, which descends into the drum through the hollow trunnion like the pipes *a* and *b*.

In order to prevent undue pressure inside the drum, openings are left at the side of the pipes *a* and *b* in the hollow trunnion.

For effecting the various kinds of operations required in the tanning process we are enabled, without stopping the motion of the drum, to withdraw therefrom by means of the pump, and discharge into the tank, the liquor that has served for a particular operation, and then to draw into the drum from the reserve-tanks the liquor that is to serve for the next operation heated to the requisite degree.

The hides, although previously prepared for undergoing the degree of treatment required in the drum, may, on account of their thickness, require a more prolonged action than is otherwise advisable; and in order to prevent fermentation under these circumstances that might be hurtful, it is requisite to maintain the liquors at a determined constant temperature, for which purpose they may be caused by means of the pump to circulate continuously from the drum through the refrigerator F and tank E back into the drum again, the action of the refrigerator being regulated to any desired extent by regulating the cold-water supply.

It will be evident that with this process may be used any known solid or liquid extracts which in a very concentrated condition will not only operate very powerfully, but also nourish the leather in a very uniform manner.

After each tanning process the liquors are caused to pass through the filters I to be clarified, so as to free them from fatty and other objectionable matters.

Having thus described the nature of our invention and in what manner the same is to be performed, we claim—

1. In apparatus for tanning, the combination of a rotating drum for receiving the hides and tanning-liquor, the liquor-reservoir E, refrigerator F, and suction and force pump B, all communicating with each other through the pipes *b*, *d*, and *a*, for operation substantially as and for the purpose set forth.

2. In apparatus for tanning, the combination of a rotating drum, A, in which the hides are subjected to the action of the tanning-liquors, a suction and force pump, B, with suction-pipe *b*, leading into the lower part of the drum, and a liquor-tank, E, into which the liquors from the drum are forced by the pump through a pipe, *d*, and refrigerator F, and from which they pass into the drum by a pipe, *a*, substantially as herein described.

3. In apparatus for tanning, the combination of the rotating drum A, pump B, tank E, filter or filters I, supplied by pipes *l* from tank E, and tanks J, for receiving the clarified liquors, from which they are conveyed back to the tank E and drum A by means of the pipes *n n* and pump B, substantially as and for the purposes described.

4. In apparatus for tanning, the combination of the rotating drum A, pump B, and tanks E. J. K. L, connected to pump B by pipes provided with stop-cocks, whereby the hides in the drum can be consecutively subjected to the action of different descriptions of tanning-liquors contained in the said several tanks, substantially as set forth.

5. In apparatus for tanning, the drum A, revolving on trunnions, through one of which inlet and outlet pipes b a enter in order to pass downward within a double side, A³, communicating with the other space of the drum by means of holes, so that the liquor can be

uninterruptedly withdrawn from and introduced into the drum while this is in operation, substantially as described.

In testimony whereof we have signed our names to this specification, in the presence of two subscribing witnesses, this 11th day of April, A. D. 1881.
